UNITED STATES PATENT OFFICE.

HERON L. KNAPP, OF WOODSTOCK, ILLINOIS, ASSIGNOR TO THE OLIVER TYPEWRITER COMPANY, OF CHICAGO, ILLINOIS, A CORPORATION OF ILLINOIS.

AUXILIARY PAPER-GUIDE FOR TYPE-WRITING MACHINES.

SPECIFICATION forming part of Letters Patent No. 761,306, dated May 31, 1904.

Application filed November 2, 1903. Serial No. 179,477. (No model.)

To all whom it may concern:

Be it known that I, HERON L. KNAPP, a citizen of the United States, residing at Woodstock, in the county of McHenry and State of Illinois, have invented certain new and useful Improvements in Auxiliary Paper-Guides for Type-Writing Machines; and I do hereby declare that the following is a full, clear, and exact description thereof, reference being had to the accompanying drawings, and to the letters of reference marked thereon, which form a part of this specification.

This invention relates to paper-guides for type-writing machines, and more especially to an auxiliary guide for use in connection with the platen of visible-writing machines, or those in which the paper at the printing-point is exposed to the eye of the operator, and which is additional or supplemental to the end guides of the platen, or those by which the side margins of the paper are held or guided in the passage of the paper around the platen.

The invention consists in the matters hereinafter described, and pointed out in the appended claims.

In the accompanying drawings, which illustrate my invention as applied to the platen-carriage of an Oliver type-writer, Figure 1 is a plan view of the main parts of the paper-carriage, showing the platen and paper-guides in plan or top view. Fig. 2 is a cross-section thereof, taken on line 2-2 of Fig. 1. Fig. 3 is a detail section taken on line 3-3 of Fig. 1. Fig. 4 is a detail section taken on line 4-4 of Fig. 1, showing a changed position of the paper-guide. Fig. 5 is a plan view, on a large scale, of the supporting-bar on which the auxiliary guide is supported. Fig. 6 is a detail cross-section of the same, taken upon line 6-6 of Fig. 5.

As shown in said drawings, A indicates the platen or printing-cylinder of the type-writer, and B B the end plates of the paper-carriage, in which the said platen is mounted.

C C' C² indicate three pressure or guide rollers by which the paper is held against the platen in its movement from beneath the

platen upward and forwardly to the top of the same or the point where the printing takes place.

D indicates a scale-bar which extends longitudinally of the platen along the printing-line and which is supported at its ends on the carriage end plates B B.

E indicates a horizontal supporting-bar which extends between and connects the end plates B B and which is located at the rear of the platen or the side of the same toward which the paper travels during the printing operation.

The paper-carriage shown in the drawings is provided with oblique paper-guides F F of the kind heretofore used on the Oliver type-writer, said guides being mounted on the ends of the supporting-bar E and terminating at their outer ends in single guide-fingers F' F', which extend transversely of the platen and bear at their free ends upon the scale-bar D. Said guides F F are supported by means of loops f f, which encircle the supporting-rod E, as in the Oliver type-writer as heretofore constructed.

Now referring to the parts more directly relating to my invention, G is a guide-rod which is arranged parallel with the platen A and which extends longitudinally of said platen at the rear of the printing-line, said guide-rod being located above the top surface of the platen between the point at which the printing takes place and the supporting-bar E, beneath which latter the paper passes as it moves rearwardly from the printing-point. Said rod G is attached to an arm G', which is supported on the bar E by means of a pivot H, affording a hinged connection between the said arm and the supporting-bar E, by which the free end of said arm G' and the guide-rod G, are adapted to swing upwardly and rearwardly from the platen. In connection with the arm G', thus pivoted to the supporting-rod G a spring I is applied between the parts and acts on the guide-rod G so as to throw the same downwardly and forwardly toward the surface of the platen. Provision is also made for limiting the downward movement

of the arm G' under the action of said spring, so that the said guide-rod will be held normally a short distance above or away from the surface of the platen.

5 Referring now more particularly to the details of construction in the parts illustrated, the pivot-pin H, which forms the hinged connection between the arm G' and the bar E, is located at the rear of said bar E, being supported in rearwardly-extending lugs e e, formed on said bar. The arm G' is arranged to extend over the upper surface of said bar E and has laterally-extending lugs g g, which project inside of the lugs e e and through 10 which the pivot H passes. Said arm G' is, moreover, adapted to rest against the top surface of the bar E when the parts are in operative position, the contact of the said arm with the bar serving to limit the downward movement of the guide-rod G. Said arm G' is, moreover, provided with a lever G², which rises from its rear margin and to which the finger may be applied for throwing the guide-bar upwardly and rearwardly against the action of the spring I. Said spring I is herein shown as having the form of a coiled spring which encircles the pivot H and which bears at one end against the lower surface of the bar E and at its opposite end against the arm 15 G', acting on the latter arm in a direction to throw the same downwardly and forwardly toward the platen. In the particular construction of the parts shown the arm G', with its lugs g g and finger-lever G², are shown as 20 made of a single piece of sheet metal so formed that in the normal position of the parts said arm G' will extend horizontally over the bar E to the front face of the supporting-bar E and downwardly over said front face of said 25 bar, the finger-lever G² being bent upwardly or at right angles to the main part of the arm G'. 30

The guide-rod G is intended to supplement the action of the paper-guides by which the side edges of the paper are guided in the passage of the sheets around the platen. When used in connection with the oblique guides F F, having the guide-fingers F' F', like those of the Oliver type-writer, such guide-rod will operate to supplement the action of said guides 45 and guide-fingers; but it may be used to perform the same function in connection with other forms of margin-guides. Said guide-rod when in its normal position adjacent to the top surface of the platen serves to hold 50 the middle part of the sheet in contact with the platen at the printing-point in cases when the sheet being printed on is so wide and the margin-guides are so far apart that the paper has a tendency to buckle up or rise at the center. While such an auxiliary guide-rod G may be useful when employed upon a type-writer carriage of ordinary length, yet the device described is more particularly designed 55 for use with very long platens or with the platens made long enough to take paper wider

than ordinary letter-paper and such as are used for special purposes, as in railway and insurance offices.

The provision of means for lifting the guide-rod G or throwing it away from the platen is 70 of considerable importance and greatly facilitates the insertion of the paper in the machine preparatory to printing. As will be readily understood by those accustomed to the operation of type-writers, when the paper is inserted in the machine and carried around the platen by the turning of the same the side edges of the paper will be confined closely against the platen by the guide-fingers F' F'; but the advance edge of the paper at its middle part is liable to be curved upwardly away from the platen, and such upwardly-curved advance edge of the paper could not be carried or inserted beneath the guide-rod g except by carefully guiding it by the fingers. 85 By lifting said guide-rod G or throwing it away from the platen as the advance edge of the paper approaches the same the said advance edge of the paper will pass beneath the guide-rod, notwithstanding that it may stand 90 some distance outwardly or away from the surface of the platen, and after the said advance edge of the paper has moved rearwardly past the guide-rod the latter may then be lowered or returned to its normal position, when 95 it will hold the central part of the paper closely to the platen or guide said paper in such manner that it will bend smoothly and evenly over or in contact with the platen at the printing-point. 100

When the paper-carriage is provided with oblique guides, such as indicated by F F in Figs. 1 and 2, these guides perform the same function as the guide-rod in holding the paper downwardly against the platen and will operate to perfectly guide the paper, so far as their influence extends. It is manifest, however, that when the platen is of considerable length the guide-rod G, which may extend along the principal part of the distance between the said oblique guides F F, will act to hold the center of the paper close to the platen in the same way that the end portions thereof are held down or guided by said oblique guides F F, while by reason of the fact that said guide-rod G is capable of movement away from the platen the paper may be readily inserted beneath the same by the lifting thereof, so that the liability is obviated of the advance edge of the sheet of paper striking the said guide-rod or striking the supporting-rod E as the advanced edges of the sheet move rearwardly over and away from the platen. 115

I claim as my invention—

1. The combination with the paper-carriage 125 of a visible-writing type-writer provided with a platen, a supporting-bar arranged parallel with the platen at the rear of the printing-point, and guides for the margins of the paper which are mounted on and extend forwardly 130

from said supporting-bar, of an auxiliary guide consisting of a supporting-arm which is pivoted to and projects forwardly from the said supporting-bar and a guide-rod attached 5 to the front end of the supporting-arm and extending longitudinally of the central part of the platen, a spring applied to yieldingly hold the said guide-rod adjacent to the platen, and means for limiting the movement of the 10 said arm toward the platen under the action of the spring adapted to hold the guide-rod out of contact with the platen; said supporting-arm being provided with a finger-piece.

2. The combination with a carriage-frame, 15 provided with a platen and a supporting-bar arranged parallel with the platen, said supporting-bar having laterally-projecting lugs which project rearwardly therefrom, of a guide-rod arranged parallel with the platen, 20 an arm which carries said guide-rod and which is pivoted to said lugs and a spring applied between the said supporting-bar and the arm and which tends to hold the guide-rod adjacent to the platen; said arm extending over 25 the top of the supporting-bar and being adapted for contact with the same to limit the movement of the guide-rod toward the platen under the action of said spring.

3. The combination with a carriage-frame, 30 provided with a platen and a supporting-bar arranged parallel with the platen, and provided with laterally-projecting lugs, a guide-rod ar-

ranged parallel with the platen, a supporting-arm attached to said guide-rod provided with laterally-projecting lugs, a pivot-rod extended 35 through the lugs on the supporting-bar and the lugs on said arm, and a coiled spring applied around such pivot-rod and acting on the supporting-bar and on the said arm, to throw the guide-rod toward the platen. 40

4. The combination with a type-writer paper-carriage provided with a platen and with a supporting-bar arranged parallel with the platen, of a guide-rod extending longitudinally of the platen, an arm which supports the guide-rod and is hinged to the supporting-bar, and an actuating-spring applied to act on the supporting-bar and the arm and tending to throw the guide-rod toward the platen, said arm being extended from the guide-bar rearwardly 45 over the supporting-bar, and having a finger-piece located at the rear of the pivotal axis thereof, so that rearward and downward pressure on said finger-piece will lift the guide-rod from the platen. 50

In testimony that I claim the foregoing as my invention I affix my signature, in presence of two witnesses, this 19th day of October, A. D. 1903.

THERON L. KNAPP.
